UNITED STATES PATENT OFFICE.

WILHO A. KOSKEN, OF NEW YORK, N. Y., ASSIGNOR, BY MESNE ASSIGNMENTS, TO
BENJAMIN FARNHAM SMITH, OF CONCORD, MASSACHUSETTS.

TWISTER RING.

Application filed February 2, 1923. Serial No. 616,500.

To all whom it may concern:

Be it known that I, WILHO A. KOSKEN, a citizen of the Republic of Finland, residing at New York, in the county of New York and State of New York, have invented new and useful Improvements in Twister Rings, of which the following is a specification.

This invention relates to twister rings of that type wherein the ring travelers are of substantial weight and are mounted in roller bearings in series on a rail.

One of the objects of this invention is to provide a construction where as large traveler rings may be employed as may have running clearance between each other. Cops or bobbins wound to comparatively large size so that replenishment is less often necessary may then be used in connection with the twisting mechanism.

A further feature of the invention relates to the manner of supporting each traveler on four rollers, the number of bearings decreasing the wear over a construction wherein fewer are employed. By utilizing all the rollers possible to support two traveler rings, each of the traveler rings may have a four roller support and yet the whole series employs only two more than twice the number of travelers.

A further feature relates to lubrication of the various traveler rings, any excess oil draining into a trough at one side of the rail where it may be readily removed.

Another feature of the invention relates to means for preventing the yarns from adjacent bobbins from becoming entangled due to the close spacing of the travelers.

Yet another feature resides in a construction wherein the roller-carrying brackets are integral with the rail.

Further features and advantageous details and combinations of parts will appear from a description of certain embodiments thereof shown in the accompanying drawings in which—

Figure 1 is a fragmentary plan of a rail showing a plurality of traveler rings in position thereon.

Figure 2 is a fragmentary plan of the rail.

Figure 3 is a section on the line 3—3 of Figure 1.

Figure 4 is a similar view showing a modified construction.

Figure 5 is a section on line 5—5 of Figure 1.

Figure 6 is a fragmentary plan showing a modification.

Figure 7 is a section on line 7—7 of Figure 6.

Referring first to the construction shown in Figures 1, 2, 3, and 5, 1 indicates the rail for supporting the ring travelers. As shown this rail comprises a casting having a series of perforated bosses spaced therealong as shown at 2 above which are positioned the ring travelers as will be described. Between adjacent pairs of bosses 2 and closer to the side edges of the rail, are other bosses 3 which are centrally perforated as at 4 for a purpose which will later appear. At one end of the rail is shown a pair of bosses 5 to which are adapted to be made fast brackets or casings 6, as shown in Figure 1, which house small end bearing rollers 7 which, as will be later described, help to support the end traveler rings of the series. At one edge of the rail is formed a trough shaped portion 10 and the upper surface of the rail between the various bosses slopes from the opposite side edge of the rail downwardly toward the trough 10 so that any oil which finds its way to the top surface of the rail is directed down to the trough where accumulations thereof may be removed by wiping the trough out as with cotton waste at intervals. The bosses 3 arranged adjacent the trough 10 are provided with extensions 12

providing vertical walls 13 extending upwardly from the inner edge of the trough. The bosses 3 along the opposite side of the rail are extended to the edge thereof as shown at 14 which edge has a downwardly extending flange 15 thereon. Bracket members 16 provided with downturned ends 17 bridge across the width of the rail, the portions 17 engaging at one side outwardly of the flange 15 and at the other side against the surfaces 13 and being fixed thereto as by bolts. These brackets therefore bridge the rail at spaced points lengthwise thereof above the bosses 3 and between the bosses 2. The intermediate portions of the brackets 16 are spaced above the rail, and above the perforations 4 therein they are provided with perforated bosses 18 in which may be

fixed journal pins or shafts 19. These pins are somewhat smaller in diameter than the 110

perforations in the bosses to permit of adjustment therein and are held in proper position by means of washers 20 and shoulders 20^a overlapping the upper and lower 5 faces, respectively, of the bosses 18 and which are clamped thereagainst by means of nuts 21 threaded on the upper ends of the pivots. The washers 20 beneath the brackets are supported on the upper faces 10 of flanged bearing rollers 25 which are journaled on the pins 19. As shown these bearing rollers each have depending bearing sockets 26 within which the pins 19 extend, these sockets 26 extending well into 15 the perforation 4 of the rail bosses 3. At the periphery of each roller is formed a downwardly extending sleeve portion 250 concentric with and spaced from the outer face of the socket portion 26 this portion 20 carrying upper and lower flanges 251. This permits a cup shaped member containing lubricant as at 27 to be held within each perforation 4 with its upper edge extending into this space. As shown the cup 27 25 is provided with an outwardly extending bead 28 adjacent its upper end by which it is supported by the edge of the perforation 4. Lubricant in these cups is permitted to reach the bearing between the pins 19 30 and the sockets 26 through openings 29 laterally of these sockets.

Positioned between the flanges 251 of the rollers and supported for rotation thereby are the ring travelers shown at 30. It will 35 be noted that these travelers, which are positioned between adjacent brackets 16, are supported entirely by the four rollers journaled therein while the end ring travelers of the series are supported by the 40 rollers of the end brackets 16 and the rollers 7 positioned at the ends of the rails. The ring travelers are supported above the perforations through the bosses 2 and concentrically therewith, the perforations 45 through these bosses, as shown, being of slightly less diameter than the central opening of the ring. Each ring, as shown, is provided with a yarn eye 31 through which the yarn passes from the usual cop or bobbin 50 (not shown) positioned below the rail in axial alinement with the ring travelers. As the strand passes up through the opening and is rotated when the mechanism is 55 in operation, it "balloons" outwardly due to the centrifugal force resulting from its rotation. As the adjacent rings are so close together since their outer peripheries almost touch, this effect if permitted would tend to cause interference between the 60 strands acted upon by adjacent rings. For preventing any such action each bracket 16 is shown as having a fin 35 projecting upwardly therefrom between its pivot pins 19; these fins forming partitions or barriers to 65 confine the strands from the travelers with-

in proper limits to prevent encroaching on the paths of the strands of adjacent rings.

For the purpose of applying lubricant to the travelers as well as to provide a retarding action to their too free rotation, 70 wiping pads may be employed, such pads being shown at 35 in Figures 1 and 5, being preferably made of felt and each partially enclosed within a channel shaped head 37 carried at the end of a leaf spring 38. 75 This leaf spring as shown is supported midway of its length on the reduced extremity 39 of an adjustable pin 40 passing through one portion 17 of a bracket 16. A coil spring 41 surrounding a larger portion 80 of the pin 40 bears at one end against a head 42 thereon which is threaded into the bracket 16 and at its other end against one face of the spring 38. The head 37 may have an opening 43 formed therein through 85 which oil may be introduced into contact with the felt 36 so as to be transmitted thereby to the periphery of the ring traveler, this in turn being engaged by the rollers 25 in the adjacent bracket 16 transferring the 90 oil to the next adjacent ring traveler and so on through the entire set of travelers. As shown the wipers are arranged in pairs at either end of a spring 38 so that they 95 need be supported only at each alternate bracket 16 throughout the length of the rail.

With this construction it is seen that each ring traveler is supported by four rollers, 100 each of the rollers carried by the bracket 16 serving to support two travelers, whereby the total number of rollers is two more than twice the number of ring travelers, these two additional being due to the end rollers 7 each of which engages only one 105 traveler. As the brackets 16 bridge across the rail the ring travelers may be of sufficiently large diameter to pass under each bracket it being necessary only that the 110 travelers should be sufficiently small to avoid actual contact in running. By employing such large travelers the winding size of the cop or bobbin may be large so that necessity of replenishment is rendered less frequent, thus saving time and labor 115 in the operation of the machine. Any excess oil above that required to properly lubricate the travelers finds its way down the inclined face of the rail to the trough 120 10 where it may be removed from time to time by running a piece of waste along the inner surface of the trough. By this means accumulation of oil which might soil the 125 work is provided.

In Figure 4 a modification has been shown in which instead of forming the brackets 16 separate from the rail and fastening thereto as by means of the bolts shown, the brackets may be made integral 130 with the rail. When this is done, in order

to be able to properly assemble the parts, it is preferable to form the bosses 3' of the rail above which the rollers are mounted sufficiently large in diameter to permit the 5 perforation 4' therethrough to be slightly greater in diameter than the diameter of the roller. The roller may then be inserted therethrough into position on the shaft 19 as shown in Figure 4 and the oil cup 27' 10 may be formed with its lower portion of sufficiently large diameter to fit snugly within the hole 4' and its upper end reduced as shown at 27^a to pass within the passage 27^b of the roller. These oil cups 15 may be held in position within the openings 4' by any suitable means such as leaf springs 50 made fast to the lower face of the rail and engaging the lower faces of the cups. As the bosses 3' must be considerably larger than the bosses 3 shown 20 in Figure 2, it may be necessary to cut away a portion of these bosses or the bosses 2 to permit passageways for the oil down the inclined upper face of the rail.

25 In Figures 6 and 7 is shown a further modification, this modification residing in the construction of the end rollers and supports which act on the end rings only. In place of the rollers 7 shown in Figure 1 a 30 pair of rollers 52 and 53 are shown which are journaled on stub axles 54 fixed to a bracket 55 upstanding from the face of the rail. These rollers 52 and 53 are spaced apart sufficiently to permit the ring traveler 35 30 to pass therebetween and one of the rollers herein shown, as roller 53, is provided with an end flange 56 to engage the outer vertical face of the ring. As shown the lower roller 53 may dip into a lubricant 40 containing cup 57 supported on a portion of the rail so that lubricant may be picked up from the cup and transferred to the ring traveler. It will be noted that in this form of the device the rollers engaging the 45 ring are journaled on horizontal axes while the ring traveler rotates about a vertical axis and that this construction permits the end rollers to be used to convey lubricant to the end traveler rings and thus to the 50 entire number of traveler rings.

Having thus described certain embodiments of this invention, it should be evident to those skilled in the art that many changes and modifications might be made therein without departing from its spirit or scope as defined by the appended claims.

I claim:

1. In a machine of the class described, a rail having a series of openings therethrough, a traveler ring arranged adjacent each opening, and oiled bearings for supporting said rings, said rail being constructed to drain surplus oil in one direction.

65 2. In a machine of the class described, a

rail having a series of openings therethrough, a traveler ring arranged adjacent each opening, oiled bearings for supporting said rings, and a trough on said rail, said rail being constructed to drain surplus oil 70 to said trough.

3. In a machine of the class described, a rail, a plurality of travelers arranged in series along said rail, and upstanding partitions between each pair of adjacent travelers.

4. In a machine of the class described, a rail, a plurality of ring travelers arranged in series along said rail, and brackets positioned intermediate each pair of travelers, 75 each of said brackets having a partition upstanding between each pair of travelers and carrying one or more rollers for supporting said travelers.

5. In combination, a rail, brackets projecting upwardly therefrom at spaced points, a pair of rollers spaced apart and rotatably carried by each bracket, and a ring traveler positioned between each adjacent pair of brackets and supported for rotation by the rollers carried by said pair of brackets.

6. In combination, a rail, brackets projecting upwardly therefrom at spaced points, a pair of rollers spaced apart and rotatably carried by each bracket, and a ring traveler positioned between each adjacent pair of brackets and supported for rotation by the rollers carried by said pair of brackets, each bracket having an upwardly projecting fin 95 acting as a barrier to prevent engagement of strands being acted on by adjacent ring travelers.

7. In combination, a rail, brackets integral therewith projecting upwardly therefrom at spaced points, a pair of rollers spaced apart and rotatable between portions of said bracket and said rail and carried by said bracket, said rail having holes in alignment with said rollers through which the rollers may be assembled in position, and a ring traveler rotatably supported by the rollers of each adjacent pair of brackets.

8. In combination, a rail, brackets integral therewith projecting upwardly therefrom at spaced points, a pair of rollers spaced apart and rotatable between portions of said bracket and said rail and carried by said bracket, said rail having holes in alignment with said rollers through which the rollers may be assembled in position, a ring traveler rotatably supported by the rollers of each adjacent pair of brackets, and lubricant containers positioned in said holes and arranged to lubricate the bearings of said rollers.

9. In combination, a rail, spaced brackets integral therewith bridging portions thereof, shafts carried by said brackets and extending into holes in said rail, rollers rota-

tably supported by said shafts, ring travelers each supported for rotation by a plurality of said rollers and projecting beneath the bridging portions of said brackets, and 5 lubricant cups positioned in said holes for lubricating said rollers.

10. In combination, a rail, spaced brackets integral therewith bridging portions thereof, shafts carried by said brackets and extending into holes in said rail, rollers rotatably supported by said shafts, ring travelers each supported for rotation by a plurality of said rollers and projecting beneath the bridging portions of said brackets, lubricant cups positioned in said holes for lubricating said rollers, and spring fingers for retaining said cups in position.

11. In a machine of the class described, a rail, a ring traveler, and means for supporting said ring traveler with relation to said rail, said means including a pair of rollers for engaging opposite faces of said ring.

12. In a machine of the class described, a rail, a ring traveler, and means for supporting said ring traveler from said rail, said means including a pair of rollers on one of which the traveler rests and the other of which is positioned thereabove.

13. In a machine of the class described, a rail, a ring traveler, and means including rollers engaging the upper and lower faces of said ring for supporting said ring from said rail.

14. In a machine of the class described, a rail, a ring traveler mounted for rotation in a horizontal plane, and a pair of spaced rollers journaled horizontally between which said ring extends for supporting the same.

15. In a machine of the class described, a rail, a ring traveler mounted for rotation in a horizontal plane, and a pair of spaced rollers journaled horizontally between which said ring extends for supporting the same, one of said rollers having a flange against which a vertical face of said ring traveler may engage.

16. In a machine of the class described, a rail, a ring traveler mounted for rotation above said rail in a horizontal plane, a pair of spaced rollers journaled on horizontal axes between which said ring traveler extends, and a lubricant-containing receptacle within which the lower of said rollers extends.

17. In a machine of the class described, a rail, a ring traveler mounted for rotation above said rail in a horizontal plane, a roller journaled on a horizontal axis and supporting said ring, and a lubricant-containing receptacle within which said roller extends.

In testimony whereof I have affixed my signature.

WILHO A. KOSKEN.
